Primary Examiner — Robert M Spear*Assistant Examiner* — Eliza Bennett-Hattan(74) *Attorney, Agent, or Firm* — QuickPatents, LLC; Kevin Prince(57) **CLAIM**

We claim the ornamental design for a banner holder, as shown and described.

DESCRIPTION

FIG. 1 is a front perspective view thereof;

FIG. 2 is an exploded front perspective view of FIG. 1;

FIG. 3 is a left-side elevational view of FIG. 1;

FIG. 4 is a right-side elevational view of FIG. 1;

FIG. 5 is a bottom plan view of FIG. 1, the top plan view being a mirror image thereof;

FIG. 6 is a front elevational view of FIG. 1; and,

FIG. 7 is a rear elevational view of FIG. 1.

The broken lines showing a banner depict environmental matter and form no part of the claimed design. The broken lines in a central portion of the banner holder depict portions of the banner holder which form no part of the claimed design.
